Primary Examiner — Sheryl Lane*Assistant Examiner* — Nicole Shiflet(74) *Attorney, Agent, or Firm* — Winston Hsu; Scott Margo(57) **CLAIM**

The ornamental design for a display screen or a portion thereof with icon, as shown and described.

DESCRIPTION

The FIGURE is a front view of a display screen or a portion thereof with icon showing my new design.

The dot-dash broken lines showing a display screen or a portion thereof define the bounds of the claimed design and form no part thereof.
